Primary Examiner — Mary Ann Calabrese*Assistant Examiner* — Natalya M Rapundalo(74) *Attorney, Agent, or Firm* — Notaro, Michalos & Zaccaria P.C.(57) **CLAIM**

The ornamental design for a pan handle, as shown and described.

DESCRIPTION

FIG. 1 is a top, front perspective view of a pan handle showing my design therefor;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

Throughout the drawing, broken lines show environment and form no part of the claimed design.

1 Claim, 6 Drawing Sheets(56)
